COMBINATION FURNITURE

Bennett Ray Jones, Perryopolis, Pa.

Application June 2, 1936, Serial No. 83,138

2 Claims. (Cl. 312—176)

My invention relates generally to combination furniture and more specifically to a combination chair and cabinet.

The invention is designed primarily to provide an easy chair for use particularly by students, or in libraries, which embodies in its construction concealed storage depositories for a number of different articles prerequisite to study, correspondence, or relaxation, as desired, all of which are compactly arranged within easy reach of an occupant of the chair.

Other objects are to provide a combination chair and cabinet which is comfortable, strong and durable, inexpensive to manufacture, and adapted for the storage of a large number of articles within a restricted space.

Other and subordinate objects, together with the exact nature of my improvements, will be readily understood when the following description and claims are read in conjunction with the drawings accompanying and forming part of the specification.

In said drawings:

Figure 1 is a view in front elevation of the combination chair and cabinet of my invention illustrating the cabinet sections opened at the front thereof.

Figure 2 is a similar view with said sections closed.

Figure 3 is a view in vertical transverse section taken on the line 3—3 of Figure 1 looking in the direction indicated by the arrows.

Figure 4 is a view in horizontal section taken on the line 4—4 of Figure 2 looking downwardly, and,

Figure 5 is a fragmentary view in vertical section of one of the cabinet sections.

Reference being had to the drawings by numerals, the combination chair and cabinet of my invention comprises a seat 1, a back 2, a removable seat cushion 3, and right and left hand end sections 4 and 5, respectively, constituting the arms and base or feet of the chair. The frame part 6 of the seat is of ornamental design, as shown. The seat, back and cushion 1, 2 and 3, are of the usual upholstered spring cushion type. The details of construction of the interiors of the parts 1, 2 and 3 are immaterial to the present invention and therefore have not been illustrated in the drawings. The seat 1 and back 2 are secured in any suitable manner between the sections 4 and 5 to be suspended thereby.

The sections 4 and 5 have the form of rectangular cabinets of uniform size, each comprising

a bottom wall 7, side walls 8, a rear wall 9, and front and top door panels 10 and 11, respectively. The door panels 10 and 11 are hinged to the sections 4 and 5, as at 12 and 13, respectively, to swing outwardly of the seat 3. The front door panels 10 are provided with a suitable form of spring latch, indicated at 14, and with tassels 15 for opening the same.

The left hand section 5 is provided with a plurality of horizontal drawers 16 slidably mounted therein on guides 17 and provided on their front ends with knobs 18. The top drawer 16 is designed as a combination smoker's tray and depository for writing equipment. For this purpose the front end of the tray is partitioned longitudinally and transversely, as at 17' and 18', respectively, to provide a cigarette tray 19 and a tray 20 for stubs or matches, having a removable ash receptacle 21 set into the bottom thereof. The rear end of said drawer 16 is partitioned transversely, as at 22, to provide a compartment 23 for writing paper or the like. The intermediate portion of said tray 16 is partitioned transversely, as at 24, to form a compartment 25 for pencils and the like, a compartment 26 provided with sockets 27 for ink bottles, and a pen-holder ledge 28. The lower drawers 16 provide ample storage space for miscellaneous articles not frequently used, for instance records or the like.

The right hand section 4 is provided with an upper shelf 29, for books, slidably mounted therein in between longitudinal guide bars 30, and the shelf is provided with a combined knob and book end 29' so that it may be pulled forwardly for access to the books thereon from the front of said section. Beneath the book shelf 29 is a magazine rack 31 comprising a rectangular vertically disposed frame 32 slidably mounted in the section centrally thereof, below said shelf between the upper and lower pairs of horizontally disposed guide bars 33 and 34, respectively. The frame 32 of the magazine rack 31 extends from the bottom wall 7 of the section to the shelf 29 and supports a pair of upper and lower troughs 35 and 36 for the magazines.

As will be seen, access may be had by an occupant of the chair to either of the sections 4 or 5 from either the top or front thereof, according to which article is desired therein and without the occupant of the chair having to rise from the seat 1. In the case of the left hand section 5, smoking and writing equipment in the top drawer 16 thereof may be easily reached by way of top panel 11 without pulling out said drawer, or, said drawer may be pulled out to locate the

contents thereof in front of the occupant of the chair and within convenient reach of other individuals. In the case of the right hand section 4, books may be had from the top of the section and, by pulling out the book shelf 29, magazines 5 may be reached from the rack 31 or both may be easily reached by pulling out the shelf 29 and said rack 31. If desired, the book shelf 29 and the rack 31 may be pulled out into extended position 10 to give the appearance of an end table at one side of the chair. When the top door panels 11 are closed, they afford broad and firm arm rests.

The foregoing description will, it is believed, suffice to impart a clear understanding of the 15 details and advantages of my invention.

It is to be understood, however, that the details set forth are illustrative rather than restrictive and that right is herein reserved to modifications of such details falling within the 20 scope of the claims appended hereto.

What I claim is:

1. A cabinet having a shelf slidably mounted therein, and a rack mounted within said cabinet adjacent said shelf and having frame members slidably engaging said shelf and a wall of said cabinet whereby to permit sliding movement of said rack to projected and retracted positions relative to said cabinet independently of any operation of said shelf. 5

2. A cabinet fashioned with guide members, 10 a shelf slidably mounted in said cabinet and equipped with guides, and a rack mounted within said cabinet adjacent said shelf and including a frame having rails, one of said rails slidably engaging said members and another of said rails 15 slidably engaging said guides whereby to permit outward movement of said shelf and rack independently of each other and relative to said cabinet.

BENNETT RAY JONES. 20
